PORTABLE TELEVISION RECEIVER

Boris Rozman, Knezova 7, Ljubljana, Yugoslavia

Filed June 20, 1972, Ser. No. 264,495

Claims priority, application Yugoslavia Dec. 20, 1971

Term of patent 7 years

Int. Cl. D14—03

U.S. Cl. D56—4 D

FIG. 1 is a front elevational view of a portable television receiver, showing my new design with the antenna extended;

FIG. 2 is a top plan view;

FIG. 3 is a right side elevational view with the antenna folded, the opposite side being substantially a mirror image thereof; and

FIG. 4 is a rear elevational view thereof with the antenna extended.

The bottom, not shown is substantially flat and unornamented.

I claim:

The ornamental design for a portable television receiver, as shown and described.
